HEAT EXCHANGER FOR GAS TURBINES

George Jendrassik, Budapest, Hungary; vested
in the Alien Property CustodianApplication April 15, 1939, Serial No. 268,009
In Hungary April 16, 1938

2 Claims. (Cl. 257—245)

The invention relates to a heat exchanger for use with a gas turbine and a compressor for preliminary compression of the working fluid. In plants of this character only moderate temperatures (500 to 600 deg. centigrade) are permissible, and it is therefore desirable to recover the heat of the spent gases from the turbine for use in heating the fresh working fluid from the compressor, in order to obtain greater efficiency. In this way the temperature of the fresh fluid of higher pressure leaving the heat exchanger to enter the turbine should approximate as far as possible the temperature of the spent gas of lower pressure leaving the turbine. This invention is designed to provide a heat exchanger for this purpose, which comprises series of metal sheets forming the flow spaces for the heat transmitting fluid from the turbine and the heat absorbing fluid from the compressor. To increase the heat transfer between these fluids, they are passed through the flow spaces in mutually opposite directions. As will fully appear from the following detailed description of the structure of the heat exchanger, this counterflow is provided by two series of passages for the heat transmitting and heat absorbing fluids respectively. By the peculiar form of the sheets, the passages of one of these series, for the heat absorbing fluid which is under higher pressure from the compressor, are formed by the spaces enclosed by the sheets, and the passages of the other series, for the heat transmitting fluid which is under lower pressure from the turbine, are formed by the spaces between sheets. These latter passages are closed along the sides of the sheets by liner bands which are provided with series of gaps or interruptions. The advantage of these gaps is that they reduce or eliminate the loss of heat caused by conduction by the liner bands from the hotter end to the cooler end of the heat exchanger. Suitable means are provided for entry and exit ports for the passages, to provide the counterflow of the fluids.

In the drawing:

Fig. 1 is a horizontal section of the heat exchanger illustrating the directions of flow of the 45 countercurrents of the heat absorbing and the heat transmitting fluids.

Fig. 2 is an enlarged perspective view of a series of sheets, the sheets being broken away to show their relation to form the alternate passages for 50 the two fluids.

Fig. 3 is a fragmentary side elevation of the series of sheets shown in Fig. 2.

Fig. 4 is a transverse vertical section through 55 a series of the sheets.

As illustrated in the drawing, the heat exchanger has an insulated casing 1 in which are disposed the substantially hexagonal sheets arranged in a series to form the passages for the fluids. For purpose of illustration, there are shown in Fig. 2 three sheets A, B and C. All the sheets are formed with parallel sides S and converging ends E with a tongue T extending outwardly from each end. The sheet A has two down-pressed ribs A—1 symmetrically disposed on either side of the longitudinal axis, parallel to the sides S and with end portions reversely turned toward the edges of the converging ends E of the sheet. The sheet B has a peripheral flange B—1, a peripheral shoulder B—2 and a raised portion B—3. The sheet B has an upwardly-pressed rib, B—4 disposed on the longitudinal axis with end portions reversely turned toward the edges of the converging ends E of the sheet. The sheet C is identical with the sheet A. As illustrated in Fig. 2, sheet B is placed upon sheet A and sheet C is placed upon sheet B. By reason of the shoulder B—2 forming the raised portion B—3 of the plate B, there is provided the passage M between sheets A and B, and by reason of the rib B—4 of sheet B and the ribs C—1 of sheet C, spacing apart the sheets B and C, there is formed the passage N between the sheets B and C (Fig. 4).

I provide the liner bands along the sides S of the sheets B and C resting upon the flange B—1 of sheet B and supporting sheet C. These liner bands L have periodic gaps G to interrupt the continuity of the bands L for the purpose hereinbefore explained.

In order to provide for the counterflow of the fluids through the passages M and N respectively, it is necessary to provide the passages with inlet and outlet ports at their respective ends, and these will now be described.

As clearly illustrated in Fig. 2, the passage M has an entry port P—1 at the near edge of the end E at the left of the figure, which is provided by interrupting the flange B—1 and shoulder B—2 of the sheet B, the exit port P—2 for passage M being provided by a similar arrangement on the far edge of the end E at the right of the figure. Since the flange B—1 and shoulder B—2 of sheet B are not interrupted at the near edge of the end E at the right of the figure and correspondingly, at the far edge of the end E at the left, the passage M is closed at those portions.

Directly above the entry port P—1 of the passage M there is provided a suitable closure block O between the sheets B and C to close the pas-

sage N, suitable packing O—1 such as solder being provided at the outer ends of block O between it and the flange B—1 of sheet B and the adjacent liner band L. A similar closure O' is provided above the exit port P—2. Since the closures O and O' are applied to the passage N only at these portions directly above the ports P—1 and P—2, the passages N have entry and exit ports P—3 and P—4 respectively directly above the closed end portions of the passages M.

As illustrated in Fig. 1, the assembled sheets A, B and C have applied thereto, at each end of the assembly, a casing 2 having a wall 2—a applied to one side of the tongues T of the sheets A, B and C and another wall 2—b extending to and applied against the ends of the liner bands L, to communicate with the ports P—1 and P—2 respectively, of the passages M. The relation of the assembled sheets A, B and C and the casings 2 is such that only the passages M communicate with the casings 2 and the passages N are so closed as not to communicate with the casings 2.

An entry pipe 3 passed through the wall 1 connects with one casing 2 and an exit pipe 4 passed through the wall 1 connects with the other casing. The pipes 3 and 4 supply the heat absorbing fluid to the passages M, through their entry and exit ports P—1 and P—2.

An entry pipe 5 passes through the wall 1 adjacent the pipe 4 and an exit pipe 6 passes through the wall 1 adjacent the pipe 3. The pipes 5 and 6, communicating with the interior of the heat exchanger, supply the heat transmitting fluid to the passages N through their entry and exit ports P—3 and P—4.

What is claimed is:

1. A heat exchanger for high pressure fluids comprising a plurality of substantially parallel spaced sheets of a general hexagonal shape, 5 means to close the peripheries of said sheets to form spaces therebetween for passage of heat exchange fluid, said means being interrupted alternately at each of the four edges of the hexagonal sheets in opposed longitudinal relation to form entry and exit ports for alternate spaces between the sheets, said means including bands between the margins of pairs of said sheets and extending longitudinally of said sheets, said longitudinally extending bands being interrupted at intervals to decrease heat transfer from one end to the other thereof.

2. A heat exchanger for high pressure fluids comprising a plurality of substantially parallel spaced sheets of a general hexagonal shape, 20 means to close the peripheries of said sheets to form spaces therebetween for passage of heat exchange fluid, said means being interrupted alternately at each of the four edges of the hexagonal sheets in opposed longitudinal relation to form entry and exit ports for alternate spaces between the sheets, said means including bands between the margins of pairs of said sheets and extending longitudinally of said sheets and in parallelism to the path of flow of said heat exchange fluid, said longitudinally extending bands being interrupted at intervals to decrease heat transfer from one end to the other thereof.

GEORGE JENDRASSIK.
